UNITED STATES PATENT OFFICE

2,410,606

ASH RECEIVER

Andrew Michyeta, Hinsdale, Ill.

Application July 30, 1945, Serial No. 607,782

1 Claim. (Cl. 220—35)

1

My invention relates to ash receivers for smoking sets and is particularly adapted for holding the ashes from cigars or cigarettes.

The main object of my invention is to provide an economical structure or means for manipulating a coniform trap door construction which is adapted to seal the cavity within the head of an ash receiver and thus safely confine ashes, cigarette butts, and cigar butts which may be in burning condition when deposited therein, preventing the same from causing accidental conflagration; in other words, the entire contraption is sealed against the outer atmospheric conditions thus causing the said burning cigarette or cigar butts, deposited therein, to be effectively snuffed out.

A specific object of my invention is to provide a closure of coniform configuration articulately and separably connected to an articulate arm which is spring urged at its mooring and adapted to retain the said coniform closure in sealing contact with an opening in the head of the ash receiving unit.

Another object of my invention is to provide a structure of the aforementioned character which is simple in construction, practical and efficient for the purposes for which it may be used, and of such simple elemental structure as to permit economical manufacture thereof in quantity production.

With these and other objects in view, one embodiment of my invention is illustrated in the accompanying drawing, where like symbols designate, or denote, like parts, and in which:

Fig. 1 is a top elevational view of my invention.

Fig. 2 is a longitudinal cross-sectional view taken, substantially, on the line 2—2 of Figure 1.

Fig. 3 is an end view of Figure 1, depicting a portion of the flange broken away in order to more clearly indicate the structural details of my invention.

Referring to the various views, my invention is, generally, designated 4 and consists of a head or inverted cup-shaped element 5, having the peripheral flange 6, which is adapted to engage a shoulder portion 26, of an ash receiver 24, which may be of any particular or specific configuration. Although the form indicated at 24 is a table type of ash receiver, the unit comprising my invention may be embodied and embraced in other structures, such as floor model types of ash receivers, or may be attached to wells in such models of receivers equipped with a mouth or opening which will accommodate the flange portion 6 thereof.

2

The said head 5 is also provided with a well 7 preferably of conical formation, and having an opening 20 therein providing access to the inner chamber of the ash receiver 24 so that the ashes 5 25 may be dropped therein. The said head piece 5 is also provided with a series of partially cylindrical indentations 8 on which a cigarette or cigar may be rested with the burning end thereof being pointed in the direction of the well 7.

10 The opening 20 is maintained sealably closed by means of a coniform structure 18 provided with a skirt portion 19, and it is to be noted, that the skirt portion 19 is of a larger diameter than the recess 20 in the head support 5. The said 15 coniform element 18 is placed in inverted relationship to the coniform well 7 as indicated in Figure 2, and has secured thereto the manipulating knob or pin 21 which is suitably undercut as indicated at 22 having its end 22 recessed so 20 as to provide an articulating connection for the articulately mounted lever or arm 16 secured at its free terminus to the hemispherical recess 23.

The lever 16 is bent to any convenient shape as indicated, one arm thereof 27 being bent to clear 25 the coniform element 18 or the skirt 19 thereof, it being also provided with a bent portion or end 28 which is articulately mounted in a U shaped bracket 9. The said U shaped bracket is provided with extensions 10 and 11, a spring being mounted about the end 28, the said spring having one 30 of its ends 13 anchored against the edge of the extension 10, its other end being elongated as indicated at 14 and provided with an attaching loop 15 which is secured to the portion 27 of the lever or arm, generally designated 16. The U shaped bracket 9 is secured to the top portion of the head 5 by means of a rivet 29 or any other suitable means.

The construction, hereinbefore described and 40 elucidated, is of such simplicity that it can be readily manufactured very economically, and I, particularly, wish to stress that the extension 17 of the arm 16 is not secured to the coniform structure but by virtue of the recess 23 the leg 45 or extension 17 articulates therein freely, and when the top 30 of the handle element 21 is depressed to the dotted position indicated by depressing it with the finger, the coniform structure closely co-acts with the tip of the extension 50 17 and cannot be jarred loose therefrom because the instant the finger hold is released at the point 30, the potential energy stored in the spring 12 is converted to kinetic energy which forces the coniform unit or element 18 to move upwardly and equalize itself within the opening 20

thus seating itself to seal the compartment of the ash receiver 24, thus preventing smoke from emanating therefrom, at the same time preventing oxygen from entering the said compartment thus having a tendency to prevent continual combustion from taking place; in other words, preventing lighted cigarette butts from continuing to burn but gradually tending to snuff them out as soon as the oxygen within the compartment in the ash receiver has been consumed.

A particular point to be stressed is that in ash receivers, wherein a well has been provided and a seal therefor, there is considerable mechanism which must be closely assembled in order to make available effective operation thereof. In this construction it can, readily, be seen that the articulate separable connection indicated at 23 working in concert with the tip of the leg 17 permits the coniform structure 18 to be confined in a manner which is readily assembled, or taken apart, and yet no particular accuracy need be observed inasmuch as the coniform structure 18 is of larger magnitude than the seal opening 20; thus both equalizing action takes place as well as perfect sealing action with the positive assurance that the coniform element 18 will always engage sealably the opening 20 in the head element 5.

The operation of my invention is clearly indicated in Figure 2 as shown by the full and dotted lines. While the dotted lines indicate a straight perpendicular travel of the handle 21, and the coniform element 18, yet it is readily deducible that the said coniform element 18 may assume any other position than that shown by virtue of the pivotal connection at 23, to the end of the leg 17 of the swinging arm or lever 16.

Through the opening thus created, and as indicated by the arrows, the ashes 25 will drop, the coniform shape of the element 18 aiding 40

into the compartment of the receiver proper. However, it is to be noted, and I wish to stress the fact, that as soon as pressure or depression force exerted at 30 is released, the entire arrangement automatically assumes the position indicated in full lines in the cross-sectional view in Figure 2.

Although, I have herein indicated a preferred structural arrangement of parts expounding the theories and practices of my invention, yet inasmuch as the same is susceptible of modifications and improvements, I hereby reserve the right to all modifications and improvements coming within the scope and spirit of my invention, as well as any implications suggested or embraced in the accompanying drawing, and also those coming within the purview of the foregoing description.

Having thus revealed and described my invention, what I claim as novel and desire to secure by Letters Patent is:

An ash tray head comprising, a cap element having an internal well portion terminating in an open portion and having an outer flanged portion adapted to be secured to an ash receiver, a bracket secured to the said cap element adjacent the said flange portion, a substantially U shaped arm having one of its legs provided with an extension pivotally secured to the said bracket, conical snuffer means provided with a base portion of greater magnitude than the said open portion, the said conical snuffer means having its apex detachably secured to the end of the free leg of the said U shaped arm by a universal joint, and spring means confined about the said extension and having one of its ends anchored to the said bracket, its other end being secured to the said first-mentioned leg of the said U shaped arm.

ANDREW MICHYETA.
